UNITED STATES PATENT OFFICE

2,290,701

MOUNTING SOCKET

Adolf G. Mueller, Fairfield, Conn., assignor to
 General Electric Company, a corporation of
 New York

Application December 16, 1941, Serial No. 423,171

2 Claims. (Cl. 173—328)

My invention relates to mounting sockets and more particularly to a mounting socket for a starting mechanism commonly employed with a fluorescent lamp of the well known type now in commercial use.

An object of my invention is to provide an improved mounting socket of the type described so constructed that the starting mechanism may be readily connected and disconnected therefrom and which permits mounting the starting mechanism at a point adjacent the fluorescent lamp.

Another object of my invention is the provision of a mounting socket for a starting mechanism which comprises relatively few parts and which may be easily assembled and manufactured at low cost.

In the accompanying drawing, Fig. 1 is a view of a fluorescent lamp and associated starting mechanism mounted in a socket constructed in accordance with my invention; Fig. 2 is a view of the starting mechanism mounted in the socket; Fig. 3 is a plan view of the socket taken along lines 3—3 of Fig. 2; Fig. 4 is a view of the interior of the socket, and Fig. 5 is an exploded view of the elements of the mounting socket.

Referring to the drawing, Fig. 1 illustrates an electric discharge device 10, such as a fluorescent lamp, supported at each end on sockets 11, the sockets themselves being supported on a mounting strip or reflector base 12 of a lamp fixture, or the like. This is one of the ways commonly employed in mounting a fluorescent lamp in fixtures for use in a wide variety of installations. Fluorescent lamps of the type mentioned require a starting switch for applying current to the cathodes of the lamp to heat them to a point at which they become emissive; the lamps also require an impedance, such as a reactor, to limit the current flow through the cathodes. Once the cathodes are heated, a discharge arc is struck between them lighting the lamp and shorting out the switch.

It is advantageous to mount the starting switch at a point where it is easily accessible for installation or replacement because in some cases, it has been found that failure of a fluorescent lighting system is due to failure of the starting switch. Failure of the reactor rarely, if ever, occurs since it is constructed of relatively rugged material and seldom needs attention. If provision is made for easy replacement of the starting switch, it is possible to take care of most instances wherein shut-down of the lamp is due to failure of the starting system.

To this end, I provide a mounting socket 13 to 55

receive a starting switch mechanism 14. These elements are constructed with coacting contact means so designed that the starting mechanism may be easily connected and disconnected from the socket 13. Removal of the switch mechanism is accomplished simply by grasping it in the hand and turning it within the socket member. The socket 13 may be mounted at any convenient point, preferably adjacent the fluorescent lamp. 5 By way of example, it has been shown mounted below the reflector surface 12. The starting switch may be any of the well known types now on the market, such as the thermal or glow discharge type. As shown by Fig. 5, the switch proper is disposed within a container 15 provided with spaced contact pins 16 having enlarged heads 17 for making an electrical connection with the socket. The contact pins 16 provide the means for mounting and supporting the starting mechanism within the socket 13 as well as providing a means for maintaining an electrical connection with the starter switch.

The socket 13 comprises two spaced parallel plates of insulating material, for example, sheet fiber. The upper plate 18 is provided with two arcuate keyhole slots 19 for receiving the contact pins 16 of the starting switch while the lower plate 20 covers the openings formed by the keyhole slots and insulates the ends of the contact pins as they are seated in the upper plate. In mounting the starting switch on the socket, the enlarged heads 17 of the starter contact pins are inserted through the large portions of the keyhole slots and then the container 15 is rotated 30 to move the contact pins to a position such that the narrower portions of the contact pins are seated in the corresponding narrower portions of the keyhole slots with the heads 17 disposed beneath the slots in the space formed between the plates 19 and 20. This means that the enlarged heads of the contact pins are locked beneath the narrower portions of the keyhole slots so that the container cannot be pulled out of the socket.

45 Cooperating with the contact pins are spaced flexible contact members 21. These contact members are disposed in the space between the upper and lower plates at points adjacent the keyhole slots so that as the contact pins in the starting switch are rotated within the keyhole slots, they engage the contact members. Each contact member is provided with an integrally formed terminal lug 22 which fits within a slot 23 formed in the lower plate so that it extends beneath the plate, as shown by Fig. 2, for con-

nection to the conductors of the lamp operating circuit. That portion of the contact member adjacent the terminal lug 22 is curved outwardly, as shown at 24. This means that in assembled position, it is spaced from the wall of the keyhole slot so that as the contact pin of the starting switch is inserted in the keyhole slot, it will not immediately engage the contact member. In order to engage the contact pin, however, the contact member is provided with an indented or projecting portion 25 which, when the contact is in assembled position, extends into the plane of the keyhole slot at a point adjacent the narrower portion of the slot so that as the starter pin is turned in the keyhole slot, it will engage the projection 25 causing the contact member to be deflected outwardly. This permits the starter pin to snap past the projection into seated position in the narrower portion of the keyhole slot. In this position, the enlarged head 17 of the contact pin engages a curved portion 26 on the contact member and is held in position by projection 25, as shown in Fig. 3.

At the end opposite that on which the lug 22 is formed, the contact member is provided with an integral tang 27 which is disposed in a recess 28 formed in the lower plate 20. It should be noted that the recess 28 is of sufficient width to permit movement of the tang 27 therein sufficient to provide for flexure of the contact member as the switch contact pins are snapped into position. The cooperating tang and slot provide a guide means for the movable end of the contact member. The contact member is normally biased into engagement with an edge 29 of the slot 28 so that it is at all times positioned correctly with respect to the keyhole slot.

It will be apparent from Fig. 5 that both of the contact members 21 are constructed exactly alike and that they are assembled in the socket simply by placing the lug 22 and the tang 27 in the corresponding slot 23 and recess 28. Thereafter, the upper plate 18 is assembled on the lower plate 20 so that the contact members are held securely in position. The upper and lower plates are held together in any suitable manner as by hollow rivets 30 which extend through openings 31 in each of the four corners of the plates. Spacer washers 32 are mounted on each of the rivets between the plates to maintain them in properly spaced position. The hollow rivets provide a simple mounting means for the socket since bolts may be passed through the rivets to fasten the socket to a support, as shown at 33 in Fig. 1.

My mounting socket is one which may be easily assembled and manufactured at low cost. To this end, the supporting plates 18 and 20 may be

punched from sheet insulating material. The contacts are simply set in the slots in the lower plate and held in position by the upper plate; no separate fastening means is required to mount the contacts in the socket. The socket is one which takes up a minimum of space in the lamp assembly.

What I claim as new and desire to secure by Letters Patent of the United States is:

1. A socket for use with an electrical device having spaced contact prongs comprising, in combination, a plate of insulating material having spaced slots and recesses therein, a pair of contact members, each contact member comprising a strip of flexible material having adjacent projecting and curved portions, each contact member being provided at one end with a terminal lug seated in a corresponding slot and a tang at the other end seated in a corresponding recess, a second plate of insulating material overlying said first-mentioned plate and being provided with arcuate keyhole slots, the projecting portions of the contact members extending into the planes of the keyhole slots at the beginning of the narrower portions of the slots, the contact prongs of the electrical device being inserted through the wider portions of said keyhole slots and snapped past the projecting portions of the contact members into seated position in the narrower portions of the slots in electrical engagement with the curved portions of said contact members, and means for fastening said plates together whereby said contact members are held in assembled relationship between said plates.

2. A socket for use with an electrical device having spaced contact prongs comprising, in combination, a plate of insulating material having spaced slots and recesses therein, a pair of contact members, each contact member comprising a strip of flexible material having a projecting portion, each contact member also being provided at one end with a terminal lug seated in a corresponding slot and a tang at the other end seated in a corresponding recess, a second plate of insulating material overlying the said first-mentioned plate and being provided with keyhole slots, the contact members being positioned between said plates with the projecting portions of the contact members extending into the planes of the keyhole slots whereby the contact prongs of the electrical device may be inserted in said keyhole slots and snapped past the projecting portions of the contact members into seated position in the slots in electrical engagement with the contact members and means for fastening said plates together.
